UNITED STATES PATENT OFFICE

IRVING J. AMATO, OF PITTSFIELD, MASSACHUSETTS, ASSIGNOR OF ONE-HALF TO
EDWARD F. FAHEY, OF PITTSFIELD, MASSACHUSETTS

POWDER DISPENSER

Application filed February 21, 1930. Serial No. 430,424.

My invention consists in the combination of a powder dispenser comprising a barrel closed at its lower end and perforated with a plurality of small holes, also in combination a powder pulverizer enclosed within the barrel working in cooperation with the small holes in the barrel.

The primary object of the invention is to provide a powder dispenser comprising a long barrel to give free access to sift the powder in places inaccessible with the ordinary powder dispenser, and also to provide means to pulverize the powder before sifting.

Another object of the invention is to provide a powder dispenser that will sift out the powder and not spray the same. Most of the spray materials are poisonous and are disagreeable in nature, and when sprayed are also more or less dangerous to the operator of the spraying device.

My invention may be used for varied purposes, such as sifting powder on plants, vines or trees, and also in the house or home as an insect destroyer.

This invention also consists in certain other features of construction and in the combination and arrangement of the several parts, to be hereinafter specifically described, illustrated in the accompanying drawings and set forth in the appended claims.

Referring to the drawings, in which like numerals of reference designate like parts in the several figures:

Figure 1 is a side view.

Figure 2 is a side sectional view.

Figure 3 is an enlarged sectional view of the barrel and pulverizer.

Figure 4 is an end view of Figure 3.

Figure 5 is a view of a modified form of my invention.

Referring to the drawings, 1 indicates a powder receptacle which is preferably of cylindrical shape with a suitable cover 2 and a handle 3. A barrel 4 is also preferably of cylindrical shape, and extends from the powder receptacle 1 and is attached thereto. The lower end of the barrel 4 is closed by means of the cover 5 which is attached thereto. The lower end of the barrel is perforated with several small holes 6 to allow

the powder in the barrel to sift therethrough. A ferrule 7 seats over the barrel and is free to move up and down and around the barrel, and this ferrule provides the means to close the perforated holes 6, by moving the ferrule 55 along the barrel and in contact with the cover 5 when the powder dispenser is not in use.

A powder pulverizer 8 fits within the barrel 1 with a small clearance between the barrel and the powder pulverizer as indicated by the numeral 16. The powder pulverizer is open at the lower end and is provided with a plurality of holes 9 around the circumference.

To facilitate the pulverizing of the powder 65 within the lower end of the barrel 4 the perforated holes 9 may be so perforated with a small burr on the outer side of the holes. The top of the powder pulverizer 8 is also provided with a plurality of holes 10 to provide means to allow powder coming from the powder receptacle 1, through the barrel 4, to enter the inside of the powder pulverizer 8.

A powder pulverizer rod 11 extends from the powder pulverizer 8 along the inside of 75 the barrel 4 and through the cover 2 of the powder receptacle. The top of the powder pulverizer rod 11 is provided with a handle bar 12 secured thereto by means of a nut 13, and a handle 14 is fastened to the handle bar 12 by means of a rivet or pin 15.

In Figure 5 I have shown a modified form of my invention in which the barrel 4 is open at the top and provided with a plug 17 through which the powder pulverizer rod 11 85 extends, and instead of the usual handle 14, as shown in Figures 2 and 3, a knob 18 is attached thereto for operating the device.

The operation of the invention is as follows: The powder receptacle 4 is filled with powder, then the ferrule 7 is moved along the barrel 4 so that the perforated holes 6 are open and exposed. The barrel 4 is placed in a depending position, and by rotating the handle 14 or the knob 18, the powder is sifted through the perforated holes 9 in the powder pulverizer 8, ground and sifted through the perforated holes 6 in the barrel 4.

What I claim is:—

1. A device of the class described comprising

ing a powder receptacle, a barrel extending from the powder receptacle having a perforated end, a ferrule adapted to fit over said perforated end, a powder pulverizer within said barrel, a pulverizer rod connected with the powder pulverizer for rotating the same.

2. A device of the class described comprising a powder receptacle, a barrel extending from the powder receptacle and closed at the outer end, said barrel having perforations located at an appreciable distance from the end, a ferrule adapted to fit over said perforated end, a powder pulverizer within said barrel, a pulverizer rod connected with the powder pulverizer for rotating the same.

3. A device of the class described comprising a powder receptacle, a cover for the powder receptacle, a barrel extending from the powder receptacle and connected thereto, said barrel having perforations located at an appreciable distance from the end, a ferrule adapted to fit over said perforated end to provide means to close and open said perforations, a powder pulverizer located within said barrel, a pulverizer rod connected with the powder pulverizer which rod passes through the cover having a handle at its outer end for rotating said powder pulverizer.

4. A device of the class described comprising a powder receptacle having a cover, a barrel extending from the powder receptacle having perforations located at an appreciable distance from the end, a ferrule adapted to fit over said perforations to provide means to open and close the same, a powder pulverizer open at one end with holes around the circumference provided with projecting rims and holes in the top, a pulverizer rod connected with the powder pulverizer which rod passes through the cover having a handle at its outer end for rotating the said powder pulverizer.

5. A device of the class described comprising a powder receptacle, a barrel extending from the powder receptacle having a perforated end, a ferrule adapted to fit over said perforated end, a powder pulverizer within said barrel and having holes around the circumference provided with projecting rims and holes in the top, a pulverizer rod connected with the powder pulverizer for rotating the same.

6. A powder dispenser comprising a barrel closed at one end with perforations located at an appreciable distance from said end, a ferrule adapted to fit over said perforated end, a powder pulverizer within said barrel, a pulverizer rod connected with the powder pulverizer for rotating the same.

7. A powder dispenser comprising a barrel closed at one end with perforations located at an appreciable distance from said end, a ferrule adapted to fit over said perforated end to provide means to close and open said perforations, a powder pulverizer within said bar-

rel provided with holes around the circumference provided with projecting rims and holes in the top, a pulverizer rod connected with the powder pulverizer for rotating the same.

In testimony whereof I affix my signature.

IRVING J. AMATO.
